The ornamental design for a “frame”, as shown and described.

DESCRIPTION

FIG. 1 is a front, right perspective view of a frame.

FIG. 2 is a front view of the frame of FIG. 1.

FIG. 3 is a rear view of the frame of FIG. 1.

FIG. 4 is a left side view of the frame of FIG. 1; and, FIG. 5 is a top view of the frame of FIG. 1. The bottom and right views of the frame of FIG. 1 form no part of the claimed design.

The features shown in dashed or broken lines depict portions of the article that form no part of the claimed design.
